UNITED STATES PATENT OFFICE.

LOUIS V. ARONSON, OF NEWARK, NEW JERSEY, ASSIGNOR TO VOICES INCORPORATED,
A CORPORATION OF DELAWARE.

SOUND DEVICE.

Application filed March 6, 1924. Serial No. 697,216.

My invention relates to improvements in sound devices and is particularly adapted for use in toys, such as dolls, to provide means therein to cause them to utter sounds like "ma-ma" etc. The main object of the invention is to provide a device of this class which is not only efficient in operation but which is also simple and unlikely to get out of order as well as being inexpensive and 10 very compact. Further and more specific objects, features and advantages will more clearly appear from the detail description given below taken in connection with the accompanying sheet of drawings which form 15 a part of this specification.

In the drawings Fig. 1 is a section through a device embodying my improvements in a preferred form thereof. Fig. 2 is a similar section showing the plunger in raised position. Fig. 3 is a transverse section taken on the line 3-3 of Fig. 1. Fig. 4 is a section through part of the plunger taken at right angles to the section of Figs. 1 and 2. Fig. 5 is a perspective of the ring for securing the tubular bellows member to the plunger and Fig. 6 is a section similar to Fig. 1 but fragmentary and illustrating a modification.

Referring to Figs. 1 to 5, a tubular cylindrical casing is indicated at 7. The casing 30 is preferably of heavy cardboard. Slidably mounted within the casing 7 is a plunger having a weighty iron member 8, circular in shape and provided with a depending circumferential flange 9 so that it is recessed on one side as indicated at 10. I find that iron serves particularly well for the weighty member of the plunger. 11 represents a tubular bellows member of 35 rubberized cloth. I find this particularly adapted as a material for the bellows since it is not only flexible but tough and substantially air-tight. One end of the bellows member 11 is secured to one end of the casing 7 by extending over the circular edge of the casing and being clamped thereto by a sheet metal cap member 12 which closes this end of the casing. The other end of bellows 11 is secured to the iron member 8 by having its periphery swedged against the inner wall 40 of the flange 9 by means of an iron ring or disc 13. The disc 13 is suitably apertured at 14 to provide for access to the corresponding side of the member 8. The member 8 is 45 apertured at 15 and extending through the

aperture 15 is a metal reed pipe 16 open on one side and having a sound reed 17 secured over the open side by a sheet metal clamp 18. The reed pipe with its reed and clamp 19 is firmly secured and sealed in the aperture 60 15 by a sealing compound such as wax or waxy material indicated at 19. The ring member 14 is shown cut away at 20 to accommodate the lower end of reed pipe and 65 reed.

22 represents a cap member having a circular depending flange 21 fitting lightly around the periphery of the plunger member 8 and forming on top of the plunger member 8 a sound chamber 23. The flat face 70 of the cap 22 is apertured at 24 to provide a sound emission opening from the sound chamber. Located on top of the cap 22 is a disc like member 25 of sheet metal which is apertured to correspond with the aperture 75 24 and which is secured to the cap by bending the edges of the cap at the periphery of the aperture 24, over the edge of the aperture in the member 25. Extending laterally from the member 25, and integral therewith, are upturned ears 26. The ears 26 are apertured near the wall of the casing and through these apertures extend pivot projections 27, integral with a flap valve 28. The flap valve 28 is made of sheet metal and 80 normally closes the sound opening 24 by gravity, and is provided with a lateral extension 29 from which the pivot projections 27 extend whereby the valve is pivoted adjacent the side wall of the casing. The 85 valve 28 is provided with an integral arm 30 extending adjacent the wall of the casing and toward the member 8; bellows 11 and the end of the casing closed by the cap 12. The valve 28 is provided with a layer 90 of fibrous material 31 on its underneath side in order that it may more effectively close the sound opening.

The side wall of the casing is cut away and apertured at 32 providing a longitudinal slot therein. 33 represents a cam member preferably stamped out of sheet metal and having lateral portions 34 which extend over the outside surface of the casing. The member 33 is provided with two stamped 100 out cam projections 35 and 36 which extend in the opening 32 in the casing wall and are adapted to engage a projection 37 on the lower end of the valve arm 30. The cam member 33 is provided with inwardly ex- 105 110

tending ribs 38 adjacent the sides of the opening in the casing and adapted to align the cam member in said opening thereby. Should the plunger with its sound chamber 5 and valve tend to rotate in the casing and throw the arm 30 out of alignment with the cams 35 and 36, the projection 37 on the arm 30 may engage the ribs 38 and thus substantially prevent any such rotary movement 10 of the plunger. The sound chamber is cut away or recessed at 39 in order to provide ample space to accommodate the valve arm 30. One of the ears 26 has an integral bent over portion 40 which acts as a stop to limit 15 the opening movement of the valve 28. That is, the stop 40 carried on the sound chamber and plunger prevents the valve opening too wide and confines the movement of the arm 30 within suitable limits. The open end of 20 the casing is shown covered with a perforated cap 41, through the perforations of which the sound is emitted.

In operation, with the parts as shown in Fig. 2, the plunger comprising the weighty 25 member 8 and parts carried thereby will slide down and descend in the casing by gravity. This causes the bellows 11 to gradually collapse and force the air therefrom through the reed pipe into the sound chamber. If the valve 28 is closed the escape of air will be so slow that the reed will not speak. When however, the plunger descends far enough for the cam 35 to engage the arm 30 and open the valve the reed will 30 speak and utter a sound like "ma" for example, the termination or interruption of which sound is effected when the plunger descends to a point where the projection 37 slides off the cam 35 and the valve 28 drops 35 under its own weight by gravity and closes the sound opening 24. When the plunger descends a slight distance further the cam 36 will engage the projection 37 on the arm 30 and again open the valve causing a second but longer sound, like "ma" for example, to be heard. That is, as the air in the 40 bellows is compressed by weight of the falling plunger the air is forced from the bellows through the reed pipe, and at those successive times when the valve 28 is open the reed will speak and the sound waves therefrom will issue into the sound chamber 23, whence they pass through the sound opening 28 and out of the device through the apertures in the cover 41. The device is then turned upside down and the plunger will move back by gravity to the position shown in Fig. 2, and the operation is repeated as often as desired. The device is compactly 45 arranged so that it is conveniently inserted in the body of a doll and is operated by reversing the position of the doll.

Referring to Fig. 6 I there illustrate a modified method of attaching the upper end 50 of the bellows member 11 to the weighty

iron head 8. In this form the depending circular flange on the member 8 is rabbeted or cut away at 42 forming a smaller circular flange of less diameter at 43. The flange 43 is provided with a peripheral groove and the upper end of the tubular bellows 11 is slipped over the flange 43 and firmly bound in the groove 44 by an encircling wire 45.

While I have thus described my improvements in great detail and with respect to 75 preferred forms, I do not desire to be limited to such details and forms since many changes may be made and the improvements embodied in widely different forms without departing from the spirit and scope thereof 80 in their broader aspects. Hence I desire to cover all modifications and forms coming within the language or scope of any one or more of the appended claims.

What I claim as new and desire to secure 85 by Letters Patent is:

1. A sound device having in combination a cylindrical casing closed at one end, a plunger adapted to slide by gravity back and forth axially of the casing, a flexible tubular 90 bellows member one end of which is connected to the casing adjacent the closed end thereof and the other end of which is connected to said plunger, a sound chamber on the opposite side of the plunger, a reed pipe 95 carried by the plunger and operatively associated with said sound chamber whereby the reed thereof will speak upon a rush of air from the bellows through the reed pipe into the sound chamber, said sound chamber having a sound opening on the side thereof opposite the bellows, a flap valve for opening and closing said opening, said valve being pivotally mounted on the sound chamber adjacent the inside wall of the casing and having an arm rigid therewith, extending toward the bellows, and a cam member extending along the wall of the casing and having two cam projections adapted to successively engage said arm to open the valve as the 100 plunger slides by gravity in the casing.

2. A sound device having in combination a casing closed at one end, a plunger adapted to slide by gravity back and forth axially of the casing, a flexible tubular bellows member 115 one end of which is connected to the casing adjacent the closed end thereof and the other end of which is connected to said plunger, a sound chamber on the opposite side of the plunger, a reed pipe carried by the plunger, and operatively associated with said sound chamber whereby the reed thereof will speak upon a rush of air from the bellows through the reed pipe into the sound chamber, said sound chamber having a sound opening, a flap valve for opening and closing said opening, said valve being pivotally mounted and having an arm rigid therewith, extending toward the bellows, and a cam member extending along the wall of the casing and 120

having two cam projections adapted to successively engage said arm to open the valve as the plunger slides by gravity in the casing.

3. A sound device having in combination 5 a casing closed at one end, a plunger adapted to slide by gravity back and forth axially of the casing, a flexible tubular bellows member one end of which is connected to the casing adjacent the closed end thereof and 10 the other end of which is connected to said plunger, a sound chamber on the opposite side of the plunger, said sound chamber being formed of a metal cup shaped member having a depending peripheral flange clampingly 15 engaging the plunger, a reed pipe carried by the plunger, one end of said reed pipe communicating with said sound chamber and the other end of said reed pipe communicating with said bellows whereby the 20 reed thereof will speak upon a rush of air from the bellows through the reed pipe into the sound chamber, said sound chamber having a sound opening, a flap valve for opening and closing said opening, said valve 25 being pivotally mounted and having an arm rigid therewith and a cam member extending along the wall of the casing adapted to engage said arm to open the valve as the plunger slides by gravity in the casing.

30 4. A sound device having in combination a tubular casing closed at one end, a plunger adapted to slide back and forth in the casing axially thereof, a flexible tubular bellows member having one end secured to the casing 35 adjacent the closed end thereof, said plunger being recessed on the bellows side thereof and a circular member holding the other end of the tubular bellows member firmly in said recess of the plunger, a cap member on the 40 other side of said plunger and forming therewith a sound chamber, and a reed pipe operatively associated therewith and adapted to speak upon operation of the bellows by the plunger, the sound from said reed 45 pipe issuing into said sound chamber.

5. A sound device having in combination a tubular casing closed at one end, a plunger adapted to slide back and forth in the casing axially thereof, a flexible tubular bellows member having one end secured to the casing adjacent the closed end thereof, said plunger being recessed on the bellows side thereof and a circular member holding the other end of the tubular bellows member firmly in said recess of the plunger, and a reed pipe operatively associated therewith and adapted to speak upon operation of the bellows by the plunger, and means for interrupting the sound from the reed pipe 60 during the movement of the plunger in one direction, said means comprising a cap member on the opposite side of the plunger from said circular member and forming a sound chamber carried by the plunger and into 65 which the sound waves from the reed pipe

issue, said sound chamber having an opening, a valve for closing said opening and a control member on the side of the casing for actuating said valve.

6. A sound device having in combination 70 a tubular casing closed at one end, a plunger adapted to slide back and forth in the casing, a reed pipe carried by the plunger and adapted to speak upon compression of air in the casing due to movement of the plunger therein, a flap valve carried by the plunger and adapted to control the sounding of said reed pipe, said flap valve being pivoted adjacent the wall of the casing and having an arm rigid therewith extending toward the closed 75 end of the casing, and a cam member on the wall of the casing adapted to engage said arm to operate the valve as the plunger moves axially of the casing.

7. A sound device having in combination 80 a tubular casing closed at one end, a plunger adapted to slide back and forth in the casing, a reed pipe carried by the plunger and adapted to speak upon compression of air 85 in the casing due to movement of the plunger therein, a sound chamber carried by the plunger and into which the sound waves from the reed pipe issue, said sound chamber having a sound opening therein, and a flap valve controlling said sound opening and 90 adapted to control the sounding of said reed pipe, said flap valve being pivoted adjacent the wall of the casing and having an arm rigid therewith extending toward the closed 95 end of the casing, and a cam member on the wall of the casing adapted to engage said arm to operate the valve as the plunger moves axially of the casing.

8. A sound device having in combination 100 a tubular casing closed at one end, a plunger adapted to slide back and forth in the casing, a reed pipe carried by the plunger and adapted to speak upon compression of air 105 in the casing due to movement of the plunger therein, a sound chamber carried by the plunger and into which the sound waves from the reed pipe issue, one end of said reed pipe communicating with said sound chamber and the other end of said reed pipe communicating with the space in the casing in 110 which the air is compressed by the plunger, said sound chamber having a sound opening, 115 therein, and a flap valve controlling said sound opening, and adapted to control the sounding of said reed pipe, said flap valve being pivoted and having an arm rigid therewith extending adjacent the wall of the casing, and a cam member on the wall of the casing adapted to engage said arm to operate the valve as the plunger moves axially of the casing, said cam member comprising a metal strip inserted in the casing wall and extending in the direction of the movement of the 120 plunger.

9. A sound device having in combination 125

- a tubular casing closed at one end, a plunger adapted to slide back and forth in the casing, a tubular bellows member, one end of which is secured to the plunger and the other end of which is secured to the casing, a reed pipe carried by the plunger, a pivoted flap valve carried by the plunger and adapted to control the sounding of said reed pipe, said flap valve having an arm extending therefrom toward the bellows end of the casing and adjacent the wall of the casing and a cam member on the wall of the casing adapted to engage said arm to operate the valve as the plunger slides in the casing.
10. A sound device having in combination a casing closed at one end, a plunger adapted to slide back and forth in the casing, a reed pipe carried by the plunger and adapted to speak upon compression of air in the casing due to movement of the plunger therein, said plunger comprising a circular member, a sheet metal cap on the circular member and forming a sound chamber into which the sound waves from the reed pipe issue, said sound chamber having a sound opening, a plate extending around said opening and provided with ears, said plate being secured to the sound chamber by the upturning of the sheet metal at the opening over said plate, a flap valve for closing said opening, said valve being pivotally mounted on said ears and having an arm extending adjacent the wall of the casing, and a cam on the wall of the casing for engaging said arm to operate the valve.
11. A sound device having in combination a casing closed at one end, a plunger adapted to slide back and forth in the casing, a reed pipe carried by the plunger and adapted to speak upon compression of air in the casing due to movement of the plunger therein, said plunger comprising a circular member, a sheet metal cap on the circular member and forming a sound chamber into which the sound waves from the reed pipe issue, said sound chamber having a sound opening, ears projecting from said cap member, a flap valve for closing said opening, said valve being pivotally mounted on said ears and having an arm extending toward said circular member and closed end of the casing and a cam on the wall of the casing for engaging said arm to operate the valve.
12. A sound device having in combination a casing closed at one end, a plunger adapted to slide back and forth in the casing, a reed pipe carried by the plunger and adapted to speak upon compression of air in the casing due to movement of the plunger therein, said plunger comprising a circular member, a sound chamber thereon into which the sound waves from the reed pipe issue, said sound chamber having a sound opening, a pivoted flap valve for closing said opening, said valve having an arm extending toward
- said circular member, said sound chamber being recessed to accommodate said arm and a cam on the wall of the casing for engaging said arm to operate the valve.
13. A sound device having in combination a casing closed at one end, a plunger adapted to slide back and forth in the casing, a reed pipe carried by the plunger and adapted to speak upon compression of air in the casing due to movement of the plunger therein, a pivoted flap valve carried with the plunger and controlling the sound from the reed pipe, said valve having an arm extending toward that face of the plunger which is opposite to the face on which the valve is located, and a cam on the wall of the casing for engaging said arm to operate the valve.
14. A sound device having in combination a casing closed at one end, a plunger adapted to slide back and forth in the casing, a reed pipe carried by the plunger and adapted to speak upon compression of air in the casing due to movement of the plunger therein, a pivoted flap valve carried with the plunger and controlling the sound from the reed pipe, said valve having an arm extending toward that face of the plunger which is opposite to the face on which the valve is located, said casing being apertured on the side thereof and a cam member extending within said aperture and secured to the casing and cooperating with said arm to operate the valve as the plunger moves in the casing.
15. A sound device having in combination a casing closed at one end, a plunger adapted to slide back and forth in the casing, a reed pipe carried by the plunger and adapted to speak upon compression of air in the casing due to movement of the plunger therein, a pivoted flap valve carried with the plunger and controlling the sound from the reed pipe, said valve having an arm extending adjacent the wall of the casing, and a plurality of cam projections carried on the casing wall and adapted to engage said arm successively to successively open said valve, said cam projections being formed on a sheet metal strip extending in the direction of movement of the plunger.
16. A sound device having in combination a casing closed at one end, a plunger adapted to slide back and forth in the casing, a reed pipe carried by the plunger and adapted to speak upon compression of air in the casing due to movement of the plunger therein, a pivoted flap valve carried with the plunger and controlling the sound from the reed pipe, said valve having an arm extending adjacent the wall of the casing, said casing being apertured on one side thereof, and a cam member secured to the casing and having a plurality of cam projections extending within said aperture to engage said arm to successively operate said valve as the plunger moves along the casing.

17. A sound device having in combination a casing closed at one end, a plunger adapted to slide back and forth in the casing, a reed pipe carried by the plunger and adapted to speak upon compression of air in the casing due to movement of the plunger therein, a pivoted flap valve carried with the plunger and controlling the sound from the reed pipe, said valve having an arm extending adjacent the casing wall, and a sheet metal cam member on the wall of the casing for engaging said arm to operate the valve, and longitudinal ribs carried by the casing wall tending to prevent rotary movement of the plunger in the casing.
18. A sound device having in combination a casing closed at one end, a plunger adapted to slide back and forth in the casing, a reed pipe carried by the plunger and adapted to speak upon compression of air in the casing due to movement of the plunger therein, a pivoted flap valve carried with the plunger and controlling the sound from the reed pipe, said valve having an arm extending adjacent the casing wall, the wall of said
19. A sound device having in combination a casing closed at one end, a plunger adapted to slide back and forth in the casing, a reed pipe carried by the plunger and adapted to speak upon compression of air in the casing due to movement of the plunger therein, a pivoted flap valve carried with the plunger and controlling the sound from the reed pipe, said valve having an arm extending adjacent the casing wall, the wall of said casing being cut away on one side, and a sheet metal cam member located thereat for engaging the arm of the valve to operate the valve, said cam member having a plurality of cam projections adapted to engage said arm and also stamped out projections for aligning the cam member with the cut away part of the casing.

In testimony whereof I have signed my name to this specification.

LOUIS V. ARONSON.
